(57) **CLAIM**

(21) Appl. No.: **29/359,001**

The ornamental design for a bracket for security camera, as shown and described.

(22) Filed: **Apr. 2, 2010**

DESCRIPTION

(51) **LOC (9) Cl. 08-05**

FIG. 1 is a perspective view of a bracket for security camera according to the present invention.

(52) **U.S. Cl. D8/363**

FIG. 2 is a front view of the bracket for security camera of FIG. 1.

(58) **Field of Classification Search** D8/363,
D8/373, 349, 354; 396/427; 248/309.1,
248/300

FIG. 3 is a rear view of the bracket for security camera of FIG. 1.

See application file for complete search history.

FIG. 4 is a left side view of the bracket for security camera of FIG. 1.

(56) **References Cited**

FIG. 5 is a right side view of the bracket for security camera of FIG. 1.
